UNITED STATES PATENT OFFICE.

CHARLES C. SPREEN, OF DETROIT, MICHIGAN, ASSIGNOR, BY MESNE ASSIGNMENTS, TO KELVINATOR CORPORATION, OF DETROIT, MICHIGAN, A CORPORATION OF MICHIGAN.

COMPRESSOR.

Application filed October 31, 1924. Serial No. 747,021.

This invention relates to compressors and has special reference to compressors such as are used for refrigerating machinery. The objects of the invention are the provision of 5 a new and improved construction of piston which shall enable the admission of the largest possible charge of gas to the compressor at each stroke and hence produce the most efficient operation; the provision of a new 10 and improved type of inlet valve which shall produce a larger effective opening with a smaller amount of movement than other valves; the provision of a valve which shall open more easily and close more tightly than 15 other piston valves; the provision of a piston and piston valve of maximum simplicity and reliability; while further objects and advantages of the invention will become apparent as the description proceeds.

20 In the drawings accompanying and forming a part of this application I have shown one of the many physical forms in which my inventive idea can be embodied although it will be understood that these drawings are 25 intended to be merely illustrative of the general principles of my invention and not to be exhaustive of its detailed application. Fig. 1 is a longitudinal sectional view of the cylinder containing the piston and piston 30 valve of my invention; Fig. 2 is an enlarged sectional view of the piston shown in Fig. 1; Fig. 3 is a top plan view of the piston drawn to reduced scale, the valve member and its securing device being limited; Fig. 4 is a top 35 plan view of a complete piston shown in Fig. 2 including its valves.

Describing the parts by reference characters appearing on the drawing, 1 denotes the outer shell of a compressor cylinder, 2 a cylinder sleeve tightly secured therein but spaced therefrom to define a gas passage 3, 4 a cylinder head or end closure, and 5 a cap member from which leads the pipe 6. Reciprocably mounted inside the sleeve 2 is a 45 piston 8 suitably articulated by means of the pitman 9 to a crank 10. This piston is formed at the end opposite the crank with a flat head 11 pierced at the center by a threaded socket 12 adapted for the reception of 50 the fillister-head screw 13, this socket being surrounded by a pair of concentric uninterrupted flanges 14 constituting a seat for the piston valve 15. This valve is annular in shape and is best made of very thin sheet

metal accurately ground to a flat surface, 55 the tips of the flanges 14 being smoothly dressed to make a tight fit therewith. The valve is held in proper relation to the valve seat by means of a suitable keeper, one form of which is shown in Fig. 2. The essentials 60 of this keeper are that it should possess a guiding portion 16 loosely surrounded by the valve disk, and a lateral flange 17 sufficiently spaced from the flanges 14 to permit a limited lift of the valve. When the keeper 65 is made separate from the screw as shown in Fig. 2 it is made with a bore 18 for the screw counterbored for the screw head. The exterior of the keeper is made plain as shown at 19. In order to prevent rotation of the 70 keeper, a dowel pin 20 inset in the piston head is preferably employed, and this, in combination with a common split washer 21 beneath the head of the screw, holds the 75 parts tightly against accidental unscrewing. The cylinder head 4 is formed opposite the center of the cylinder with a bore 22 snugly receiving the boss 19, and the adjacent portion of the closure is recessed as shown at 23 for the reception of the flange 17, thus enabling the piston to move completely to the 80 end of the cylinder and eject substantially all the gas therefrom.

Between the flanges 14 the piston head is formed with an annular recess shown at 24 85 and into this recess open a plurality of gas inlet passages 25. When a sleeve type cylinder is employed as shown in Fig. 1 the passages 25 preferably open into an annular duct 26 formed in the head of the piston, 90 this duct communicating by means of ports 27-27 with a shallow external annular recess 28 formed between the two ends of the piston. Between the piston head 11 and the upper end of this recess the piston is 95 formed with suitable grooves 30 for the usual piston rings and below this groove the exterior is preferably formed with a cylindrical land 31 which engages the cylinder wall in steadyng relation. When this wall 100 consists of a sleeve as shown in Fig. 1 it is formed at a suitable height with one or more ports 32, 32 which at all times establish communication between the annular space 3 and the recess 28. The gas to be compressed is 105 admitted to the space 3 in any suitable manner as by the lateral boss 33 or by ducts 34 from the crank case.

Having thus described my invention what I claim is:

In a compressor, a piston having an annular valve seat, an annular valve adapted to engage said seat, a keeper having a guiding portion traversing the hole in said valve and having a lateral flange overhanging said valve in a position to limit its displacement

from said seat, a screw extending thru said keeper into the piston head, said keeper having a central socket for the reception of the screw head, and a lock washer between said keeper and screw head. 10

In testimony whereof, I hereunto affix my signature.

CHARLES C. SPREEN.
